ATOMIZER

Max L. Goldbert, New York, N. Y.

Application July 27, 1944, Serial No. 546,767

8 Claims. (Cl. 299—88)

My invention relates generally to atomizers, and in particular it relates to atomizers which provide means for varying the character of the spray. The main object of my invention is the provision of an atomizer which disseminates fluid material in various degrees of diffusion.

A further object of my invention is the provision of an atomizer in which a plurality of tubes are provided extending from the fluid material to be dispensed to the atmosphere, and a spray head is provided which is shiftable into cooperative relation with any one of the tubes, as desired.

Still another object of my invention is the provision of an atomizer having a plurality of tubes of different diameter, and a spray head which may be selectively associated with one or the other of the tubes, whereby the character of the spray may be varied.

Other and further objects of my invention will be specifically pointed out in connection with the following description of an illustrative embodiment, and still others will be apparent therefrom. It is, of course, to be understood that my invention is not to be limited to the specific form shown, but only by the scope of the claims appended hereto.

In the drawing annexed hereto and forming a part hereof,

Figure 1 is a top plan view of one form of device constructed according to and embodying my invention;

Fig. 2 is a vertical section on the line 2—2 of Fig. 1;

Fig. 3 is a vertical section on the broken line 3—3 of Fig. 1; and

Fig. 4 is a horizontal section on the line 4—4 of Fig. 2.

My device, indicated generally by reference numeral 10, comprises a housing 12 formed as by molding, casting or other process, of any suitable metallic, plastic or other material. Housing 12 has a pair of longitudinally extending chambers 14, 15 therein; the smaller chamber 14 opening upwardly towards the top of the housing, the larger chamber 15 opening downwardly towards the bottom of the housing. An air passageway 30 is formed through the body of housing 12, between the chambers 14, 15, leading from the bottom of chamber 14 to the atmosphere, venting through the top of housing 12 above chamber 15.

Chamber 14, circular in cross-section, comprises the pump chamber. I dispose therein a relatively elongated piston rod 16, having a circular washer 18, of rubber, leather or other suitable material,

5 at the bottom thereof sealing against the sides of the pump chamber. The mouth of chamber 14 is internally threaded, as indicated at 20, and there is screwed or otherwise fixed therein a plug 22, through a central aperture in which piston rod 16 projects. A cap or button 26 is fixed to the top of piston rod 16, and is provided with an annular notch or groove 25 which cooperates with a finger piece 24 extending upwardly from plug 22 into the recess 24. A vertical slot 27 is formed in cap 26 below notch 25, and upon rotation of the cap to bring finger piece 24 into line with slot 27, the shaft or plunger may be permitted to rise upwardly and out of the chamber. A coil spring 10 28 is disposed on the floor of chamber 14, bearing against the underside of washer 18 and tending normally to urge washer 18 and shaft 16 upwardly. A plurality of air inlet openings 24, 24 are also provided through plug 22.

In Fig. 2, piston rod 16 is shown locked within pump chamber 14, for convenience in carrying the device. When cap 26 is released from finger 15 24, the piston is spring-28-urged upwardly, and pressure exerted downwardly against cap 26 25 forces a blast of air through passageway 30 and out of the housing through the spray head.

Housing 12, at the top thereof above chamber 15, is recessed to receive therewithin a spray head 32, which is locked onto the housing by means of 30 a headed bolt 34 bearing against the underside of the housing wall. Head 32 is apertured, as at 36 and is provided with an air jet 38 at the top thereof having an offset nozzle 40. Head 32 may be pivoted about bolt 34, a handle 42 being secured 35 to the head for that purpose, for reasons which will be developed below.

A fluid container, as 50, may be inserted within chamber 15, the open mouth 52 thereof bearing against a washer 54 secured to the underside of 40 the housing wall by bolt 34. A leaf spring 56, pivotally secured to floor 58 of pump chamber 14 by rivet 60, urges container 50 against the washer seal 54. The bottom of housing 12 may be enclosed by a cap 62 force fitted onto reduced neck portion 64 of the housing, so that a smooth surface is presented. When the fluid material M in container 50 is exhausted, cap 62 45 may be removed, spring 56 pivoted away from the underside of the container, and the container removed, refilled and reinserted, or a new full container inserted.

A pair of tubes 70, 72 are provided, of different internal diameters, tube 70 being of very small diameter, and tube 72 of much greater diameter. Both tubes are of equal length, and extend

through the top of housing 12 towards the bottom of container 50, housing 12 and washer 54 being suitably aperatured to permit the tubes to extend therethrough. The tops of tubes 70, 72 are level with the end of jet nozzle 40, and head 32 may be pivoted to bring jet nozzle 40 into close proximity with the ends of either of the tubes, as desired, by actuation of lever arm 42. Stops 74, 76 are provided atop housing 12 to limit the movement of nozzle 42 and properly locate jet nozzle 40 with respect to the mouths of tubes 70, 72.

When it is desired to disseminate fluid M in a very fine spray, jet nozzle 40 is associated with the fine tube 70, but when it is desired to disseminate the fluid material in coarser, droplet form, handle 42 is swung into the dotted line position (Fig. 1) and nozzle 40 brought into proximity to the wider tube 72.

My device is small, neat and compact, and its choice of sprays renders it extremely useful in connection with medicating the nasal or oral areas. The main feature thereof is its choice of sprays, and the ease with which, in the one device, the character of the spray may be varied.

Having now described my invention, what I claim and desire to secure by Letters Patent is:

1. In an atomizer, a pump chamber, an air outlet, a communication between the pump chamber and the outlet, a fluid reservoir and a plurality of tubes projecting thereinto from the atmosphere, and means to associate the air outlet with any of the tubes.

2. An atomizer, as in claim 1, in which the tubes are of different diameters, and the character of the spray is varied in accordance with the tube associated with the air outlet.

3. In an atomizer, a pump chamber, an air outlet, a communication between the pump chamber and the outlet, a fluid reservoir and a

plurality of spaced-apart tubes projecting thereinto from the atmosphere, and means to move the air outlet into association with any of the tubes.

4. An atomizer, as in claim 3, in which the tubes are of different diameters, and the character of the spray is varied in accordance with the tube associated with the air outlet.

5. In an atomizer, a pump chamber, an air outlet therefrom, comprising a nozzle, an air passageway between the pump chamber and the nozzle, a fluid reservoir and a plurality of spaced-apart tubes projecting thereinto from the atmosphere, means to shift the nozzle to selectively associate the said nozzle with any of the tubes.

6. In an atomizer, a housing, a pump chamber therewithin, an air nozzle on the housing, a communication between the pump chamber and the air nozzle, a fluid reservoir within the housing, a plurality of tubes extending into the fluid reservoir and upwardly of the housing, and means to associate the air nozzle with any of the tubes.

7. An atomizer as in claim 6, in which the nozzle is mounted on the associating means which is located midway between the tubes and which is rotatable.

8. In an atomizer, a housing, a pump chamber therewithin, an air passageway through the housing, an air exit port, said port comprising an angled terminal nozzle, a fluid reservoir, a plurality of tubes from the reservoir to the atmosphere, the ends of which tubes are at substantially the same level as the nozzle, certain of the tubes being of greater diameter than others thereof, and means to rotate the nozzle to alter the direction of the air blast from the pump chamber, through the air passageway and out at the nozzle end and thereby to bring the air nozzle into cooperative relation to any of the tubes.

MAX L. GOLDBERT.
